UNITED STATES PATENT OFFICE.

WILLIAM E. BORTON, OF OMAHA, NEBRASKA.

MOTOR-VEHICLE-LOCKING MEANS.

1,305,519.

Specification of Letters Patent. Patented June 3, 1919.

Application filed October 29, 1917. Serial No. 199,183.

To all whom it may concern:

Be it known that I, WILLIAM E. BORTON, a citizen of the United States, and a resident of Omaha, in the county of Douglas and State of Nebraska, have invented certain new and useful Improvements in Motor-Vehicle-Locking Means, of which the following is a specification.

My invention relates to mechanism for preventing the starting or operation of internal-combustion engines by unauthorized persons, and is particularly intended for use in preventing theft of motor vehicles driven by engines of this class. It is the object of my invention to provide a lock-controlled valve in the pipe or conduit through which the combustible charge is supplied to an internal-combustion engine, whereby the possessor of a suitable key may readily open the valve to enable operation of the engine, while without the proper key to open the valve the engine cannot be run to produce power. A further object of my invention is to provide a valve device of the character above indicated, which may be readily and easily inserted at a joint usually found in the intake pipe connections of internal-combustion engines, so that the locking device is applicable to the engine with a minimum disturbance of the ordinary engine fittings. A further object of my invention is to provide means controlled by the valve-lock to prevent disconnection of the inserted valve-casing or valve-carrying section of the pipe from the adjacent portions of the charge-conducting conduit.

In the accompanying drawings, Figure 1 is a side view of an engine provided with a valve device embodying my invention, Fig. 2 is a transverse section of the valve-casing showing the valve in open position, Fig. 3 is a similar view with the valve in closed position, Fig. 4 is partially a plan view and partially a section on the plane of the line 4—4 of Fig. 3, and Fig. 5 is a section on the plane of the line 5—5 of Fig. 3.

In Fig. 1 there is shown an internal-combustion engine of a common type having an intake manifold-pipe M terminating in a portion 6 provided with a coupling-flange 7 which is usually connected by suitable bolts with a similar flange 8 on the carbureter or charge-forming device C. My valve and locking device is applied to the engine by disconnecting the flanges 7 and 8, inserting the valve-casing 9 between them, and con-

necting said flanges and casing by means of special bolts, hereinafter described. The main body of the valve-casing 9 is formed similarly to the flanges 7 and 8, and has a longitudinal passage 10 of the same size as that through the pipe-portion 6, but at one side of the casing there is a projecting cylindrically-recessed portion 11. Within said part 11 there is fitted the barrel 12 of a lock, preferably of the well-known "Yale" type, having an eccentrically disposed cylinder 13 provided with a slot for receiving a key 14, and the key having a serrated edge-portion for controlling a series of spring-actuated tumbler-pins 15. The structure and operation of the lock proper will be readily understood; it being noted that when the key is inserted in the cylinder the ends of the tumbler-pins are thereby moved into register with the periphery of the cylinder, so that the latter may be rotated; and that when the cylinder is turned from the locked position thereof the tumbler-pins prevent withdrawal of the key from the slot. The lock is so arranged that the axis of the cylinder 13, if prolonged, intersects the axis of the passage 10 through the valve-casing, and a valve-rod or shaft 16 is provided which extends across said passage, said shaft fitting revolvably within openings through the casing and having a head 17 which is secured to the inner end of the cylinder by screws 18. The portion of the shaft 16 within the passage 10 has a transverse slot in which the valve-disk 19 is inserted and secured by means of pins or rivets 20. The diameter of the valve-disk is substantially the same as that of the passage, so as to close the same when extending perpendicularly to the axis thereof, as shown in Fig. 3. The parts are so connected that the valve is in said closed position when the cylinder 13 is in the locked position shown in said Fig. 3. At one side of the passage 10 there is a stop-pin 21 which is engaged by the valve-disk when the latter is turned to a position parallel with the axis of the passage, as shown in Fig. 2 and by dotted lines in Fig. 5. A coil spring 22 is disposed around the valve-shaft adjoining the head 17, one end of the spring being turned in and inserted through an opening in the shaft, and the other end of the spring being inserted in an opening in the end of the barrel 12, to connect the same therewith. Said spring is under tension such that it tends to turn the valve toward the open posi-

tion thereof and retain the same at said position with the disk 19 in engagement with the stop-pin 21, thereby preventing movement of the valve to closed position except by intentionally turning the key and cylinder to the locking position thereof and withdrawing the key from the cylinder.

The valve-casing 9 has longitudinal openings adapted to register with the bolt-holes 10 through the flanges 7 and 8, so that bolts 23 may be passed through said openings to secure the casing between the flanges. The openings for the valve-shaft are preferably arranged so that they intersect the sides of the bolt-holes through the casing, and the 15 bolts have annular concave grooves 24 therein at longitudinal positions such that said grooves register with the shaft-openings. In the sides of the valve-shaft, adjoining the 20 bolt-holes, there are notches 25 so arranged that when the valve is in open position, as shown in Fig. 2, said notches are in register with the bolt-holes, thus enabling the bolts to be inserted through the holes or withdrawn 25 therefrom. When the valve is in the closed and locked position shown in Fig. 3, portions of the valve-shaft lie in the grooves 24 of the bolts and prevent withdrawal of the bolts from the valve-casing. By dis- 30 posing the heads of the bolts oppositely to each other, as shown in Fig. 4, the valve-casing is prevented from being disconnected from either of the flanges 7 and 8 while the valve is in locked position, since the flange 7 35 is held against the casing by the head of one bolt, and the flange 8 similarly held by the head of the other bolt, even if the nuts should be removed from the threaded ends of the bolts. Thus when the valve is in the 40 locked position thereof, access thereto by any person not having a key for the lock is practically impossible, and, as the charge-inlet passage to the engine is closed by the valve, the engine cannot be run.

45 The special utility of the locking device for preventing theft of motor-vehicles will be obvious, as removal or disablement of the locking device cannot be effected without the use of special tools and the expenditure of 50 considerable time, which are not usually available to persons engaged in such practices. The locking device is also such as to comply with traffic regulations in cities, the device permitting the vehicle to be pushed 55 or pulled, but not under its own power, as when required to be moved for short distances during absence of the owner.

Now, having described my invention, what I claim and desire to secure by Letters Patent is:

1. Locking means for preventing opera-

tion of an internal-combustion engine, comprising the combination with separable flanged portions of the charge-supplying pipe of the engine, of a valve-casing inserted between said flanged pipe-portions, said casing having a passage connecting the passages through said pipe-portions, a valve for closing the passage through the casing, locking means for retaining the valve in closed position, bolts extending through the casing and the flanges of the pipe-portions to secure said parts together, and means controlled by the valve-locking means for preventing withdrawal of the bolts from the casing when the valve is closed.

2. Lock-controlled means for preventing operation of an internal-combustion engine, comprising the combination with separable flanged portions of the charge-supplying pipe of the engine, of a valve-casing inserted between the flanges of said pipe-portions, bolts extending through the casing and connecting said flanges therewith, a valve controlling a passage through the casing between and connecting the passages of said pipe-portions, a key-controlled lock-member for actuating said valve, and means controlled by said lock-member for preventing withdrawal of the flange-connecting bolts from the valve-casing.

3. Means for preventing operation of an internal-combustion engine, comprising in combination separable portions of the charge-supplying pipe of the engine, a valve-casing disposed between said separable pipe-portions and having a passage connecting the passages through said pipe-portions, a valve disposed in said connecting passage, a shaft carrying said valve, a key-controlled lock-cylinder fixedly connected with said shaft and adapted to retain the same in valve-closing position, resilient means connected with said shaft and tending to move the same to valve-opening position, members extending through the casing and said pipe-portions to fixedly connect the same, and means controlled by rotation of the valve-carrying shaft for preventing disengagement of said connecting members from the valve-casing.

4. In a device of the class described, a valve-casing, a valve controlling a passage through said casing, a key-controlled cylinder, a shaft connecting said cylinder and the valve, said shaft having portions adapted to intersect bolt-holes through the casing, and bolts extending through said bolt-holes, said bolts being grooved transversely to receive the portions of said shaft that intersect the bolt-holes.

W. E. BORTON.
